AEROFOIL

Application filed August 8, 1927, Serial No. 211,428, and in Great Britain April 12, 1927.

This invention consists of an aerofoil of a novel and useful character, adapted for the purpose of controlling the movements of aircraft.

5 One object of the invention is to enable an aeroplane to be controlled by using the present invention in substitution for the usual ailerons thereby avoiding some of the disadvantages attendant upon the use of the latter, 10 as at present designed, particularly the difficulty of operating them against heavy wind resistance.

Another object is to stabilize an aeroplane by means of aerofoils in place of ailerons, 15 which will improve the lateral balancing up to and even beyond the usual stalling angle and to simplify the mechanism by which these aerofoils are operated.

A further object is to improve the steering 20 of aircraft by employing my proposed aerofoil as a rudder.

A still further object is to use the proposed aerofoil as an elevator.

Other objects and advantages of the invention 25 may become apparent from the description which follows.

Broadly, the invention when serving the function of improved ailerons, comprises or 30 consists of aerofoils which are mounted so as to be capable of turning horizontally or thereabouts through 90° or any other desired angle on a vertical or inclined axis, and each one is so designed as when in flight to induce a lifting effect when rotated to one position and a 35 depression when rotated to the other, these merging into an intermediate neutral position. The turning axis will, of course, be horizontal, when the aerofoil is used as a rudder.

40 In the accompanying drawings, Figs. 1 and 2 illustrate the invention diagrammatically;

Figure 3 represents an aeroplane to which the invention is shown, by way of example only, applied in a particular manner, the rear 45 portion of the aeroplane being left out.

Figures 4 and 5 are (on a larger scale) a plan and an elevation respectively of one end of the wing shown in Fig. 3, together with the aileron therein illustrated.

50 Figure 5^a is a view similar to 5 but showing

a slight variation in the mounting. Figure 6 is a section on line 6^x of Fig. 4.

The principle underlying the invention is exemplified in a simple manner by the arrangement illustrated in Figures 1 and 2 in each of which an aileron A, illustrated as rectangular-shaped for simplicity, is shown mounted askew upon a vertical central axle B, the mounting being a rigid one. The aileron A is, for illustrative purposes, shown merely a flat blade, and the plane in which it lies is essentially not normal to the axis about which it turns. Let it be assumed that the aileron A is attached to the wing tips of an aeroplane, as illustrated in Figs. 3 to 6, the aeroplane being regarded as moving through space in the direction opposed to the arrows, from left to right, as viewed in Figs. 1 and 2. Therefore, each of such ailerons presents to the wind a deflecting surface alternately at 65 the upper and lower faces according to the position to which it has been turned by the partial rotation of the axle B. Figure 1 indicates the wind, (by arrows X X) impinging upon the under surface of the blade A and Figure 2 shows by arrows Y Y the wind blowing upon the upper surface of the blade A. 70

With the aileron A occupying the position of Fig. 1, the wing E to which it is attached will become raised, since the wind pressure indicated by the arrows X X exerts a lifting 80 pressure on the aileron A. With the aileron occupying the position of Fig. 2, on the other hand, the wing E will become lowered, the wind pressure indicated by the arrows Y Y 85 exerting a depressing force. In Fig. 1, the aileron A is said to have a positive angle of incidence; in Fig. 2, the angle of incidence is said to be negative.

Referring now to the particular construction and design represented in Figures 3 to 6, which illustrate a simple embodiment of my invention, each aileron or aerofoil is shaped roughly circular or oyster-like, as seen in plan with two major axes *m* of equal length intersecting at right angles to each other, but not centrally of the figure. The sectional shape upon each of the said axes *m* is shown streamlined or cambered upon one face (see Fig. 5) and approximately flat or straight- 90

lined on the other face (see *f* Fig. 5). The term "flat" or "straight-line" face is used herein only as indicating that it corresponds with the chord of the cambered surface, being in reality curved when viewed from the direction of flight.

The strictly flat or straight-line formation is not, however, essential. As will be understood by persons skilled in the art, the face *f* 10 may be considerably varied without at all departing from the spirit or scope of the invention. It is important that the positive angle of incidence of the aileron *D*, in relation to the angle of incidence of the wings *E*, shall be small, while the corresponding negative angle of incidence shall be large. As is 15 clearly illustrated by the full-line, sectional showing of Fig. 6, this result is very efficiently attained by having the face *f* approximately straight or flat, within the above definition of the term. The aileron *D* then presents to the wind a cambered upper surface *c* and flat lower surface *f*. In the opposite, or negative, extreme position, of course, 20 represented by the section shown in dotted lines in Fig. 6, the upper surface *f* of the aileron *D'* is shown approximately flat or straight and the lower surface *c* cambered.

The aerofoils above described will be conveniently located at the outer or further ends of each plane or wing *E*, one upon each, and owing to their being rotatably mounted upon a vertical or partly vertical axis, the effort required to operate them will be markedly 25 less than what is required for ailerons of the ordinary hinged type.

An example of their mounting is shown in Figures 3, 4, 5 and 5^a, in which the rotary axle *B* of the aerofoil *D* is seen to be carried 30 by a bracket *G H* comprised by three arms, two of which *G* radiate from the axis *B* in a horizontal plane and are attached at their ends to the lower edge of the plane *E*, and another arm *H* extends in an inclined direction 35 from the axis *B* to the thick or forward part of the plane *E*, where it is fastened to the top of the latter, the arms *G* and *H* forming a three-dimensional and, therefore, rigid structure. The inclined arm *H* incidentally 40 occupies a position nearer to the line of the under face of the aerofoil *D* when the rotary axle *B* is upright as in Fig. 5 than when it is inclined, as in Fig. 5^a. These are given only 45 as illustrations of possible types of mountings and they could be varied in any desired manner.

Appropriate gear of any known kind can be adapted for the purpose of operating the ailerons or aerofoils *D*.

The means of operating the ailerons or aerofoils represented by way of example in Figures 3 to 6 consists of a grooved pulley *J* fast upon the axle *B* and a wire cord *K* passed around same and suitably connected to the control 'stick' in any convenient manner as

will be well understood, preferably so as that only one is operated at a time. It is thus possible to move either aileron *D* without the other, so that movement of the aileron that is situated on that side of the machine which it is required to lower may be effected without movement of the other aileron.

The two extreme positions of the ailerons *D* are shown in Figures 4 and 6, the full outline *D* denoting the position of maximum lift, 70 with the aileron *D* facing the opposing wind, and the dotted outline *D'* the maximum depression, the angle between these positions being 90°, though any other suitable angle could be used if the shaping of the aerofoil were suitably modified. Between these two extreme positions, it is possible to obtain infinitely small variations, there remaining a neutral position when the forces upon each face of the aerofoil are mutually balanced.

A combination of aerofoils, as above described, may be mounted and adapted for use as elevators.

When the aerofoil, above described, is to be used as a rudder, its axle will be set horizontally and any suitable means of operating such rudder can be employed.

The ailerons may be mounted in such a position, and with their axles *B* so placed, that the gap or clearance between the wing *E* and the aileron *D* increases as either aileron *D* is moved to give a depressing force (i. e. moved to their negative angle of incidence) and vice versa.

I claim:—

1. An aileron having two opposed convexly curved surfaces adapted to be subjected to the action of wind pressure, a rotatable axle about which the aileron is eccentrically mounted to turn, and means for rotatably adjusting the aileron about the axle to present different portions of the surfaces to the wind pressure, each surface having curves of different curvature in cross-sectional planes substantially at right angles to each other, 100 with the curve of greater curvature of one surface and the curve of lesser curvature of the other surface in one of the planes and the curve of greater curvature of the said other surface and the curve of lesser curvature of the said one surface in the other plane.

2. A rotary aileron or aerofoil roughly circular or oyster-like in shape, an axle eccentrically fixed thereto, the plan shape of said aileron or aerofoil having two major axes 110 intersecting one another at right angles or thereabouts, the cross sectional shape upon one of said axes being a figure bounded by a camber upon a straight (or approximately straight) line and upon the other of said axes a straight (or approximately straight) line connecting the extremities of an inverted camber and projecting means (connected to the wing) about which said axle may rotate to vary the distance between the wing tip 120

and the peripheral edge of the said aileron or aerofoil.

3. A rotary aileron or aerofoil roughly circular or oyster-like in shape, an axle eccentrically fixed thereto, the plan shape of said aileron or aerofoil having two major axes intersecting one another at right angles or thereabouts, the cross sectional shape upon one of said axes being a figure bounded by a camber 10 upon a straight (or approximately straight) line and upon the other of said axes a straight (or approximately straight) line connecting the extremities of an inverted camber, said axle being located at or near the intersection 15 of the said axes and projecting means (connected to the wing) about which said axle may rotate to vary the distance between the wing tip and the peripheral edge of the said aileron or aerofoil.

20 4. A rotary aileron or aerofoil roughly circular or oyster-like in shape, an axle eccentrically fixed thereto, the plan shape of said aileron or aerofoil having two major axes intersecting one another at right angles or thereabouts, the cross sectional shape upon 25 one of said axes being a figure bounded by a camber upon a straight (or approximately straight) line and upon the other of said axes a straight (or approximately straight) line connecting the extremities of an inverted camber, said axle being located at or near the intersection of the said axes and means connecting said axle with the control stick of the aeroplane so that the aileron or aerofoil may be operated independently of a similar one fitted to the other wing.

35 5. A rotary aileron or aerofoil roughly circular or oyster-like in shape, an axle eccentrically fixed thereto, the plan shape of said aileron or aerofoil having two major axes intersecting one another at right angles or 40 thereabouts, the cross sectional shape upon one of said axes being a figure bounded by a camber upon a straight (or approximately straight) line and upon the other of said axes a straight (or approximately straight) line connecting the extremities of an inverted camber, projecting means (connected to the wing) about which said axle may rotate to 45 vary the distance between the wing tip and the peripheral edge of the said aileron or aerofoil, and means connecting said axle with the control stick of the aeroplane so that the aileron or aerofoil may be operated independently of a similar one fitted to the other wing.

55 6. A rotary aileron or aerofoil roughly circular or oyster-like in shape, an axle eccentrically fixed thereto, the plan shape of said aileron or aerofoil having two major axes intersecting one another at right angles or thereabouts, the cross sectional shape upon 60 one of said axes being a figure bounded by a camber upon a straight (or approximately straight) line and upon the other of said axes a straight (or approximately straight) line connecting the extremities of an inverted camber, said axle being located at or near the

intersection of said axes, and means connecting said axle with the control stick of the aeroplane so that the aileron or aerofoil may be operated independently of a similar one fitted to the other wing, projecting means (connected to the wing) about which said axle may rotate being provided to vary the distance between the wing tip and the peripheral edge of the said aileron or aerofoil. 70

7. A rotary aileron or aerofoil roughly circular or oyster-like in shape, an axle eccentrically fixed thereto, the plan shape of said aileron or aerofoil having two major axes intersecting one another at right angles or thereabouts, the cross sectional shape upon 75 one of said axes being a figure bounded by a camber upon a straight (or approximately straight) line and upon the other of said axes a straight (or approximately straight) line connecting the extremities of an inverted camber, said axle being located at or near the intersection of the said axes and means connecting said axle with the control stick of the aeroplane so that the aileron or aerofoil may be operated independently of a similar one fitted to the other wing. 80

8. A rotary aileron or aerofoil roughly circular or oyster-like in shape, an axle eccentrically fixed thereto, the plan shape of said aileron or aerofoil having two major axes intersecting one another at right angles or thereabouts, the cross sectional shape upon one of said axes being a figure bounded by a camber upon a straight (or approximately straight) line and upon the other of said axes a straight (or approximately straight) line connecting the extremities of an inverted camber and projecting means (connected to the wing) about which said axle may rotate to vary the distance between the wing tip and the peripheral edge of the said aileron or aerofoil, and to give a greater negative than positive angle of incidence. 90 100

9. A rotary aileron or aerofoil roughly circular or oyster-like in shape, an axle eccentrically fixed thereto, the plan shape of said aileron or aerofoil having two major axes intersecting one another at right angles or thereabouts, the cross sectional shape upon one of said axes being a figure bounded by a camber upon a straight (or approximately straight) line and upon the other of said axes a straight (or approximately straight) line connecting the extremities of an inverted camber, said axle being located at or near the intersection of the said axes and projecting means (connected to the wing) about which said axle may rotate to vary the distance between the wing tip and the peripheral edge of the said aileron or aerofoil and to give a greater negative than positive angle of incidence. 110 115

In witness whereof I have signed this specification.

KENNETH NOBLE PEARSON. 130
